COMBINED MOVING PICTURE PROJECTOR AND FILM EDITOR

William Castedello and Edward K. Kaprelian, Plainville,
Conn., assignors to The Kalart Company Inc., Plain-
ville, Conn.

Application April 1, 1954, Serial No. 29,798

Term of patent 7 years

(Cl. D61—1)

FIG. 1

FIG. 2

To all whom it may concern:

Be it known that we, William Castedello and Edward K. Kaprelian, both citizens of the United States of America, residing in Plainville, county of Hartford, and State of Connecticut, have invented a new, original, and ornamental Design for a Combined Moving Picture Projector and Film Editor, of which the following is a specification, reference being had to the accompanying drawings, forming a part thereof.

Fig. 1 is a front perspective view of a combined moving picture projector and film editor, showing our new design, and

Fig. 2 is a side elevational view thereof, as seen from the right hand side of Fig. 1.

We claim:

The ornamental design for a combined moving picture projector and film editor, as shown.
